Patented July 7, 1903.

UNITED STATES PATENT OFFICE.

WILLIAM A. SPICER, OF PROVIDENCE, RHODE ISLAND, ASSIGNOR TO
BARSTOW STOVE COMPANY, OF PROVIDENCE, RHODE ISLAND.

DESIGN FOR A CONNECTED BRACKET AND HIGH SHELF FOR STOVE-RANGES.

SPECIFICATION forming part of Design No. 36,415, dated July 7, 1903.

Application filed April 21, 1902. Serial No. 104,051. Term of patent 14 years.

To all whom it may concern:

Be it known that I, WILLIAM A. SPICER, a citizen of the United States, residing at Providence, in the State of Rhode Island, have 5 invented a new, original, and ornamental Design for the Connected Bracket and High Shelf of a Stove-Range.

The accompanying drawing represents a perspective view of a connected ornamental 10 bracket and high shelf embodying my design.

I claim as my invention—

The ornamental design for the connected bracket and high shelf of a stove-range, as shown.

WILLIAM A. SPICER.
